attorney.

UNITED STATES PATENT OFFICE.

SVEN T. NELSON, OF CHICAGO, ILLINOIS, ASSIGNOR TO SULLIVAN MACHINERY COMPANY, A CORPORATION OF MASSACHUSETTS.

TEMPERING MECHANISM.

Application filed August 7, 1922, Serial No. 580,239.

To all whom it may concern:

Be it known that I, SVEN T. NELSON, a citizen of the United States, residing at Chicago, in the county of Cook and State of Illinois, have invented certain new and useful Improvements in Tempering Mechanism, of which the following is a full, clear, and exact specification.

My invention relates to tempering mechanism for mining machine cutter bits.

It has for its object to provide an improved tempering mechanism for such bits whereby, as distinguished from subjecting the entire bit to the tempering process as heretofore, it is made possible to temper only the working end or point of the bit and thereby materially improve the effectiveness of the bit by maintaining the body of the same relatively soft in such manner that the set screws holding the bit in position during cutting, as for instance when used in a mining machine cutter chain, may better grip the bit and as a result hold it more firmly in position on its link.

In the accompanying drawings I have shown for purposes of illustration one form which my invention may assume in practice.

In these drawings,—

Fig. 1 is a diagrammatic side elevation partially in section of my improved mechanism, showing a furnace and my tempering mechanism arranged beside the same.

Fig. 2 is a detail view of a portion of the conveyor, showing the bit carrying means thereon.

Fig. 3 is a transverse section of the conveyor shown in Fig. 2 showing a bit in position thereon.

In this illustrative construction, I have shown my tempering mechanism used in connection with a bit heating furnace 1 which may be of any suitable form and is preferably located adjacent the tempering mechanism so that an operator may remove the bits from the furnace and conveniently place them upon a moving part of the tempering mechanism.

As shown, this mechanism is entirely automatic and comprises a conveyor 2 in the form of a flat, elongated, metal strip having upstanding bit receiving stall forming members 3 spaced along the working face thereof and power driving and guiding means herein including one or more suitable power sprockets 4, herein two, driven

from a suitable source of power at a suitable speed, and a plurality of guiding sprockets 5 so disposed as to direct the conveyor from a point adjacent the furnace operator's station laterally and downward into a suitable bath 6 such, for example, as a water bath, with only the tips of the bits entering the liquid and then upward from that bath and over an incline and downward into another suitable bath 7, such as an oil bath, through which the bits are similarly passed with only their tips engaging the liquid, the conveyor discharging the bits automatically into a suitable receptacle 8 after they have passed out of the bath 7 and then following a path 70 beneath the baths 7 and 6, respectively, back to the starting point.

As a result of my improvement, it will be noted that the difficulty heretofore resulting from tempering the entire bits and the consequent production of bits having hard shanks difficult for the set screws to grip, has been eliminated, only the tips of the bits in my improved construction being subjected to the bath or baths. It will further be observed that as a result of my improved construction, it is possible, by regulating the speed of the conveyor or the path thereof, to regulate the time that the bits are subjected to any bath.

While I have in this application specifically described one form which my invention may assume in practice, it will be understood that this form of the same is shown for purposes of illustration and that the invention may be modified and embodied in various other forms without departing from its spirit or the scope of the appended claims.

What I claim as new and desire to secure by Letters Patent is:

1. In a tempering mechanism for blanks, a tempering bath, and a conveyor for moving and entirely supporting a blank in such manner that only the end is immersed.
2. In a tempering mechanism for blanks, a tempering bath, and a conveyor to move and entirely support a series of blanks adjacent said bath so that only the ends are immersed.
3. In a tempering mechanism for blanks, a tempering bath, and means above said bath to move and entirely support a series of blanks successively above said bath so that only the ends are immersed.
4. In a tempering mechanism for blanks

having laterally extending ends, a tempering bath, and means above said bath to move and entirely support a series of blanks successively above said bath so that only said ends are immersed.

5. In a tempering mechanism for blanks having laterally extending ends, a tempering bath, and a conveyor having blank receiving means disposed thereon adapted to support 10 a series of blanks above said bath so that only said ends are immersed.

6. A tempering mechanism for mining machine cutter bits comprising a conveyor system having provision for supporting a bit 15 with its point disposed below the conveyor, a bath, and means for passing said conveyor over a bath in such manner that only the point of the bit is immersed.

7. In a tempering mechanism for mining 20 machine cutter bits, a tempering bath, a conveyor having provision for supporting and moving a series of bits over said bath so that only the points are immersed, and guiding and driving means for said conveyor.

8. In a tempering mechanism for mining machine cutter bits, a tempering bath, a conveyor, bit holding means formed on said conveyor, means to move said conveyor over 30 said bath so that only the points of the bits are immersed, and means to automatically discharge said bits.

9. A tempering mechanism for cutter bits comprising a conveyor system having provision for supporting a bit with its point disposed below the conveyor, a plurality of baths, and means for passing said conveyor successively over said baths in such manner that only the point of the bit is immersed.

40 10. A tempering mechanism for cutter bits comprising a conveyor system having provision for supporting a bit with its point disposed below the conveyor, a water bath, an oil bath, a bit receptacle, and means for 45 passing said conveyor relative to said elements in such manner that the point only of a bit is immersed in said water and oil baths successively and that the bit is subsequently discharged into said receptacle.

50 11. In a tempering mechanism for blanks, a tempering bath, means to move and en-

tirely support a series of blanks successively adjacent said bath with only the ends immersed, and means to automatically discharge said blanks.

12. In a tempering mechanism for blanks, a tempering bath, and means to move and entirely support a series of blanks adjacent 60 said bath in such manner that only a portion of the blanks are immersed, said means comprising a flexible endless conveyor.

13. In a tempering mechanism for blanks having projecting portions formed thereon, a tempering bath, and a conveyor adapted to support entirely a series of blanks above 65 said bath so that only the projecting portions are immersed, said conveyor having means formed thereon engaging the sides of said blanks to position the latter.

14. In a tempering mechanism for blanks 70 having downwardly extending portions formed thereon, a tempering bath, and means above said bath to move and entirely support a series of blanks successively above said bath with said portions projecting from 75 said means so that only said portions are immersed.

15. In a tempering mechanism for blanks, a tempering bath, a conveyor having provision for entirely supporting and moving a 80 blank adjacent said bath so that only the end is immersed, and guiding and driving means for said conveyor.

16. In a tempering mechanism for blanks, a tempering bath, a conveyor having provision for supporting and moving a series of 85 blanks adjacent said bath so that only a portion is immersed, said conveyor having apertures formed therein, and guiding and driving means for said conveyor including 90 sprockets cooperating with said apertures.

17. In a tempering mechanism for cutter bits comprising a conveyor system having provision for supporting bits with their points projecting laterally from said conveyor, a tempering bath, and means for moving and supporting said bits in such manner that only the points of the bits are immersed.

In testimony whereof I affix my signature.

SVEN T. NELSON.
